UNITED STATES PATENT OFFICE.

DESIRE H. VAN HOVE, OF JACKSON, MICHIGAN, ASSIGNOR TO REYNOLDS SPRING COMPANY, OF JACKSON, MICHIGAN.

UPHOLSTERED SPRING STRUCTURE.

Application filed December 7, 1922. Serial No. 605,489.

To all whom it may concern:

Be it known that I, DESIRE H. VAN HOVE, a citizen of the United States, residing at Jackson, in the county of Jackson and State 5 of Michigan, have invented new and useful Improvements in Upholstered Spring Structures, of which the following is a specification.

The invention relates to an upholstered 10 spring structure.

The object of the present invention is to provide for upholstered spring structures a base frame equipped with means for supporting the spring structure and for securing 15 the marginal springs to the base frame and to the marginal springs at the lower ends thereof.

A further object of the invention is to provide a base frame of this character adapted 20 to hold the leather or other material, of which the flexible covering is constructed, smoothly in position so as to present a neat finish and to protect the flexible covering from wear, abrasion or other injury at the 25 point of attachment of the covering to the base frame and to the spring structure.

With these and other objects in view the invention consists in the construction and novel combination and arrangement of parts 30 hereinafter fully described, illustrated in the accompanying drawings and pointed out in the claim hereto appended, it being understood that various changes in the form, proportion and minor details of construction, 35 within the scope of the claims, may be resorted to without departing from the spirit or sacrificing any of the advantages of the invention.

In the drawings, in which like characters 40 of reference designate corresponding parts in the several views:—

Figure 1 is a vertical sectional view of a portion of a spring structure provided with a marginal base frame constructed in accordance 45 with this invention.

Figure 2 is an enlarged detail sectional perspective view of a portion of the base frame illustrating the manner of attaching the marginal springs and the flexible covering.

Figure 3 is a detail perspective view of a portion of the main strip.

Figure 4 is a similar view of a portion of the auxiliary interlocking, clamping strip.

55 In the accompanying drawing, in which is

illustrated the preferred embodiment of the invention, the base frame comprises in its construction a main strip 1 and an auxiliary interlocking clamping strip 2 constructed of sheet metal or other suitable material and 60 designed in practice to extend around the four or more sides of a spring structure, such as a spring seat of an automobile or the like. The main strip is composed of upper and lower approximately horizontal 65 sides 3 and 4, and an inner connecting portion or bend 5. The upper and lower sides 3 and 4 are spaced apart to form an approximately U-shaped body portion, and the lower side 4, which is extended outwardly beyond 70 the upper side, is provided at the outer edge with an upwardly extending longitudinal flange 6, which is nearly vertical and which is adapted to be compressed or bent inwardly to close the space between 75 the upper and lower sides 3 and 4 at the outer portion of the main strip to confine the lower marginal portion 7 of a flexible covering 8 in the longitudinal opening or space between the upper and 80 lower sides of the main strip. The main strip in practice is preferably constructed of heavy material, and the narrow upper side 3 is provided with an upwardly extending approximately vertical flange 9, which is 85 spaced from the upwardly extending flange 6 of the lower side before the said flange 6 is bent inwardly to confine the marginal portion of the flexible covering within the main strip for fastening the said marginal covering 90 to the base frame. The marginal portion of the flexible covering 8 is preferably provided with a hem 10 formed by folding the material on itself and stitching the folded portion and a core 11, consisting of a rod 95 of metal or wood, or other suitable material, is preferably arranged within the hem to provide a bead or marginal enlargement, which is confined within the main strip and which effectually prevents the flexible covering 100 from accidentally slipping out of the base frame. The marginal portion of the flexible covering may be constructed in any other desired manner as will be readily understood.

The interlocking auxiliary strip 2, which is 105 reversely arranged with respect to the main strip, is composed of upper and lower spaced sides and an outer curved connecting portion or bend 12, which presents a smooth 110

supporting surface to the flexible covering 8 at the attached marginal portion thereof, and it enables the flexible covering to be stretched taut without liability of tearing 5 or otherwise injuring the flexible covering. This also enables the flexible covering to be maintained in a smooth neat condition at the point of attachment to the base frame. The lower side of the auxiliary clamping strip 10 extends into the main strip and fits against the inner or lower face of the upper side of the said main strip, while the inner face of the bent or connecting portion 12 fits against and is braced by the upwardly extending 15 flange 9 of the said upper side 3 of the main strip. The upper side of the auxiliary clamping strip is adapted to be compressed or pinched around the upper and inner side faces of the lower end coils 13 of the coiled 20 or volute springs 14 of the spring structure and the compressed or pinched portions 15 of the upper side of the auxiliary strip securely fastens the marginal springs upon the main strip of the base frame, which supports 25 the said marginal springs. The spring structure, which may be of any preferred construction, consists of rows of the said coiled or volute springs coupled or otherwise connected together at their upper and lower 30 ends and preferably provided at their upper ends with a marginal frame 16.

The main and auxiliary strips are adapted to be easily and quickly assembled, and the said strips may be readily compressed to 35 fasten the marginal springs and the marginal portion of the flexible covering to the base frame.

What is claimed is:

1. In a spring structure, a base frame comprising a main approximately U-shaped strip having spaced upper and lower sides and an inner connecting portion and provided at the outer edges of the sides with projecting flanges, the flange of the lower side being 40 adapted to be bent towards the upper side to close the space between the said sides to confine a flexible covering therein, and a reversely arranged auxiliary clamping strip interlocked with the main strip and having 45 an exterior flange adapted to be compressed around the upper and inner faces of the lower end coils of the marginal springs of a spring structure to secure the marginal springs upon the main strip.
2. In a spring structure including a base frame comprising a main strip approximately U-shaped in cross section having spaced upper and lower sides, the lower side being extended outwardly beyond the 50 upper side and the said sides being provided at their outer edges with projecting longitudinal flanges, the flange of the lower side being adapted to be bent inwardly towards the upper side to confine a flexible covering

in the main strip and an auxiliary clamping 65 strip interlocked with the main strip and having an exterior flange located above the upper side of the main strip and adapted to be compressed around the lower end coils of the marginal springs of a spring structure. 70

3. In a spring structure including a base frame comprising a main strip approximately U-shaped in cross section having spaced upper and lower sides, the lower side being extended outwardly beyond the upper 75 side and the said sides being provided at their outer edges with projecting longitudinal flanges, the flange of the lower side being adapted to be bent inwardly towards the upper side to confine a flexible covering in 80 the main strip, and a reversely arranged auxiliary clamping strip approximately U-shaped in cross section having upper and lower sides, the lower side extending into the main strip and the upper side being located above the same and adapted to be compressed around the lower end coils of the marginal springs of a spring structure 85 to secure the marginal springs upon the main strip. 90

4. In a spring structure including a base frame comprising a main strip approximately U-shaped in cross section having spaced upper and lower sides, the lower side being extended outwardly beyond the upper side and the said sides being provided at their outer edges with projecting longitudinal flanges, the flange of the lower side being adapted to be bent inwardly towards the upper side to confine a flexible covering in 95 the main strip, and a reversely arranged auxiliary clamping strip composed of upper and lower sides and an outer connecting portion fitted against and braced by the upwardly extending flange of the upper side of the main strip and presenting a convex exterior surface to the flexible covering, said auxiliary clamping strip having its lower side extending into the main strip and its upper side located above the same and adapted to be compressed to clamp springs 100 of a spring structure on the main strip. 105

5. In a spring structure, a main strip of approximately U-shape, having upper and lower sides and provided at the upper side with a substantially vertical projecting longitudinal flange and an auxiliary clamping strip of approximately U-shape reversely arranged with respect to the main strip and having its lower side extending into the main strip and its upper side located above the same, said auxiliary clamping strip fitting against the said flange and braced by the same and adapted to clamp springs on 110 the main strip. 115

In testimony whereof I have hereunto set my hand.

DESIRE H. VAN HOVE.
